UNITED STATES PATENT OFFICE.

LEO L. BARRON, HARRY B. WOLKEN, AND FRANK J. FELKER, OF ST. LOUIS, MISSOURI.

WASHING-MACHINE.

1,369,876.

Specification of Letters Patent.

Patented Mar. 1, 1921.

Application filed September 7, 1920. Serial No. 408,537.

To all whom it may concern:

Be it known that we, LEO L. BARRON, HARRY B. WOLKEN, and FRANK J. FELKER, citizens of the United States, residing at St. Louis, Missouri, have invented certain new and useful Improvements in Washing-Machines, of which the following is a specification containing a full, clear, and exact description, reference being had to the accompanying drawings, forming a part hereof.

Our invention consists in the novel disclosure and construction hereinafter particularly described and distinctly claimed.

15 The object of our invention is to provide an improved apparatus for washing clothes in water, and cleaning clothes in gasoline or other volatile liquid; whereby the goods or clothes being cleaned or washed will be subjected to a vacuum or suction action, a squeezing action, and a forcing action, all while the clothes are in the water or other cleansing liquid, to the end that the clothes will be quickly and thoroughly cleansed unharmed.

20 A further object of our invention is to provide an improved washing-machine which shall accomplish the above-named object rapidly, efficiently, and at a low cost.

25 In the drawings,

Figure 1 is a vertical longitudinal section of a washing machine constructed in accordance with our invention.

Fig. 2 is a vertical cross-section of the same, taken on the line 2—2 of Fig. 1.

Fig. 3 is an enlarged inverted plan-view of one of the plungers of the machine, and

Fig. 4 is a detail side-elevation of the hollow partition which separates the two clothes chambers, and yet provides a clear water-passage from one chamber to the other, at the lower edge of said partition, and at the bottom of said clothes chambers.

45 The numeral 1 designates a tub, which may be made of sheet-metal, of wood, or partly of metal and partly of wood, of any desired dimensions, to suit the designer, and to meet the requirements of the quantity of clothes to be washed at a time.

50 Said tub 1 is mounted, in the present illustration of our invention, upon a suitable rectangular frame 2.

Any common form of a cover 3, may be provided for the top of the said tub.

55 The tub 1 is divided by a hollow sheet-metal partition 4 into two clothes-chambers

5 and 6, which separate the clothes contained in each chamber, and keep them separated during the washing or cleaning operation; but said hollow partition is constructed, as shown, so as to provide a series of unobstructed water-passages 7 beneath the body of said partition, extending from the bottom of one of said clothes chambers into the other, so that (as far as the water is concerned) the water may pass freely from one chamber to the other, and back again, as often as the plungers move up and down in said chambers.

55 Mounted in each of the clothes chambers 5 and 6, to forcibly move up and down therein above the clothes, is a plunger 8, which fits the vertical walls of the chambers at its edges, and whose under-side is provided with a series of vacuum or air-chambers 9, formed by projecting strips 10 upon the bottom of the plunger, so that said bottom is divided into a series of such air chambers by said strips, as shown more clearly in Fig. 3.

Common vertical strips 11, Fig. 1, may be used to assist in holding said hollow partition 4 in a vertical position in the tub, said strips being soldered or otherwise secured to the vertical walls of the tub and partition.

The said plungers may be moved up and down in any desired manner, or by any approved means, either from the top of the machine, or from beneath the tub, which latter construction we have herein shown, and in which a common form of electric-motor 90 12 is mounted upon a platform 14, in the space beneath the tub 1, and connected by means of a pinion 15 to a gear-wheel 16, for the purpose stated.

Vertical plunger-rods 17 pass upwardly 95 and downwardly through vertical water-tight chambers 19 formed in the said hollow partition 4, at a point near the center of the length of the latter, and the top and bottom of said plunger-rod chambers 19 are fitted 100 with covers or caps 20 which are perforated for the passage of said rods, and which should be heavy enough to act as proper bearings, to guide said rods in their vertical movement.

105 Apertures are formed in the bottom of the tub 1 for the passage of the said plunger-rods 17, but a water-tight joint should be formed between said bottom and the said adjacent lower ends of said plunger-rod chambers 19, 110 by soldering or clamping the parts together, as shown in Fig. 4.

Lubricating waste 21 surrounds and lubricates the said plunger-rods in said chambers 19, and said waste also acts as a packing, to prevent the passage of liquid into said chambers from the top.

For detachably connecting the plungers 8 to the said plunger-rods 17, we have shown here an L-shaped arm 22, the horizontal part of which is perforated near its end and 10 clamped in position upon a bearing-head 23 at the upper end of each plunger rod, by means of a common thumb-screw 24, which passes through the perforation of said arm and is threaded into the said bearing-head 15 23, Fig. 1.

The shorter vertical arms of the said L-shaped arms 22 are yieldingly connected to the top of said plungers 8, in a proper manner, as will now be described.

20 Said shorter vertical arms are tubular, and they are telescopically engaged by a vertical shank 25 rising from a base-plate 26 which is secured to the top of said plungers by means of screws or rivets 27, so that as 25 the said plungers are brought down into contact with the clothes, the said shank 25 will be pushed farther into the said vertical arms, until their springs 28 are compressed, thereby preventing any violent shock; said 30 springs being located on said shanks between the ends of said vertical arms and the said base-plates 26.

Movement of the said shanks 25 downwardly in said tubular vertical arms of 35 said parts 22, is limited by a stop-pin 29 carried by said shanks and engaging the lower ends of guide-slots 30 formed in said vertical arms.

By this construction, the plungers 8 may 40 be removed to place clothes in the clothes chambers, merely by loosening and detaching said thumb-screws 24.

After the clothes have been washed or cleaned, they may be quickly removed from 45 the clothes chambers by detaching the said thumb-screws 24 and lifting out the said plungers.

A common rack, or slatted or reticulated structure, 31, is placed on the bottoms of 50 the said clothes chambers 5 and 6, to hold the clothes off of the bottoms of said chambers, and to allow the water or other cleansing liquid to pass freely beneath the clothes from one of said chambers to the other, through 55 the said water-passages 7 beneath the said hollow partition 4.

The said pinion 15 is fixed on the armature-shaft 32 of said motor 12, and a crank-pin 33 is fixed to one face of the gear-wheel 16.

60 A connecting-rod 34 has its lower end

mounted on said crank-pin 33 and its upper end pivoted at 35 to the lower end of the said plunger-rod 17, to reciprocate the plunger 8 in said clothes chamber 6.

65

The plunger in the other clothes chamber 5 is driven (in the present case) by a crank-disk 36 mounted on the end of a short shaft 37 which carries said gear-wheel 16 at its opposite end and is mounted in a bearing at 70 the upper end of a bracket 38 resting upon said platform 14.

Another connecting-rod 39 has its lower end mounted on a crank-pin 40 carried by the said crank-disk 36, and the upper end 75 of said connecting-rod is pivotally-connected at 41 to the lower adjacent end of the plunger-rod 17 of the plunger that operates in clothes chamber 5.

The operation of our invention will be apparent, without further description, except to call attention to the fact that the method or process of washing clothes with water, as herein shown and described, may be used in cleaning garments with gasoline or other 80 volatile liquids, by merely substituting the latter for water and soap.

We claim:—

An improved washing machine, comprising two chambers; a hollow partition which 90 separates said chambers except at the bottom of the latter, where a free and unobstructed water-passage is formed beneath said partition, through which the water may pass from one of said chambers to the other 95 chamber; separate vertical water-tight plunger-rod chambers located in said hollow partition at a point near the center of the length of the latter; perforated caps for the upper and lower ends of the said water-tight 100 partition chambers; vertical plunger-rods operating through said water-tight partition chambers and their perforated caps; plungers arranged to fit the walls of said first-mentioned chambers; L-shaped arms which 105 connect said plungers to the upper ends of said plunger-rods; and driving-mechanism connected to the said plunger-rods, to reciprocate the same, and thereby force said plungers up and down alternately, to squeeze 110 the cleansing liquid through the clothes in one of said first-mentioned chambers, thence into and through the said water-passage beneath said hollow partition into the other one of said first-mentioned chambers, and thence 115 back to the starting chamber.

LEO L. BARRON.
